SPOOL CONSTRUCTION

George G. Tucker, Jr., Berwyn, Ill., assignor to
 Hubbard Spool Company, Chicago, Ill., a corporation of Illinois

Application August 24, 1949, Serial No. 112,017

2 Claims. (Cl. 242—123)

1

This invention relates to improvements in a reel or spool structure for supporting wire, cord, thread, or similar material. More particularly, this invention has to do with a spool having improved and strengthened head members.

Spools adapted for carrying material such as thread or wire must be of a rigid construction having all the elements suitably secured together. Although material such as thread or wire is comparatively light when it is wound on a spool, it builds up a heavy pressure against the head, and, therefore, the spool must be so constructed that the heads are strong and rigid and accurately maintained with their inner faces in radial planes so that the head will not spread under the heavy pressure built up during winding. Unless such accurately dimensioned and rigid structure is provided for the spool, the winding of the thread or wire will not be uniform and regular and the thread will catch and snarl during unwinding of the spool.

It is, therefore, an important object of my invention to construct a spool of this type of relatively light-gauge sheet metal, such as steel, with the various sheet metal elements arranged and rigidly secured together, as by brazing, for cooperation to produce a rigid structure which will maintain its proper shape and resist deflection or distortion.

Another object of this invention is to produce a spool constructed of comparatively light-gauge sheet metal parts in which each head is in the form of a sheet metal disk stiffened, strengthened and braced by a reinforcing web structure stamped integral from sheet metal with stiffening ribbing and secured to the head disk to form a strong head structure which will resist and withstand the spreading strains imposed thereon.

Another and further object of this invention is to provide a simplified efficient means for securing and holding various parts of a spool intimately together in assembled relation.

Other and further objects, features and advantages of the present invention will become apparent to one skilled in the art from the following detailed description taken in connection with the accompanying drawing:

On the drawing:

Figure 1 is an end elevational view of a spool constructed in accordance with the teachings of the present invention.

Figure 2 is a fragmentary vertical sectional view taken on line II—II of Figure 1, partly in elevation, particularly illustrating the head construction of this spool.

2

As shown on the drawing:

In Figures 1 and 2, the reference numeral 10 indicates a spool comprising two disk-like head assemblies 12 mounted at either end of a cylindrical hub 14.

Each head assembly 12 includes a ring-shaped plate 16 having an outer curled peripheral edge 18 and an axially extending inner cylindrical flange 20 that defines a circular opening 22 in the plate 16. The plate 16 has a plurality of arcuate apertures or slots 24 that are spaced angularly in relation to each other on a common radius from the axis of the ring-like plate. These slots 24 are arranged to receive tabs 26 that project axially from the end of the cylindrical hub 14. When the tabs 26 are inserted through the slots 24, they are bent over to lie flat against the face of the plate 16.

It will be understood, of course, that the head assemblies 12 at each end of the spool are exactly alike and are connected to the hub portion in an identical manner.

In each head assembly, the plate 16 is reinforced by an annular plate or washer 28 that has a curled peripheral outer edge 30 that fits snugly under the curled edge 18 of the plate 16. The washer 28 lies flat against the plate 16 and has a series of spaced, axially deflected portions 36 forming recesses over the turned-down tab members 26. The outer surface 38 of the recesses lies in a plane defined by the ends of the curled edge 18 of the plate 16, and cooperates therewith to provide a flat, end surface for the spool.

The outer surfaces 38 of the recesses are blended into the main portion of the washer 28 by inclined transition portions 40 that also act as reinforcing ribs lending rigidity to the structure.

The washer 28 has a central opening defined by an axially extending cylindrical flange 42 that projects into the hub 14 in close fitting engagement with the flange 20 of the end plate 16. A tubular insert 44 telescopes inside the flange 42 and has an outwardly flared end portion 46 that overlaps the rounded portion 48 of the washer 28.

The cylindrical hub 14 and the insert 44 may be made from seamless tubing or, as shown in Figure 1, they may be formed from a flat plate which is bent around a mandrel to form a cylindrical member and spliced at their abutting ends by means of a strip 50 welded to each member.

Four spaced lug holes 52 are provided in the washer as well as a plurality of drain holes 53. Drain holes 54 are also provided at the outer rim 55 of the washer. Further, a hole 56 is provided in

the head near the surface of the hub 14 to receive the beginning end of the wire or thread, and a hole 58 is provided near the outer end for receiving the end of the wire or thread.

After the various elements of the head are assembled together on the hub and on the insert, the abutting surfaces are copper brazed so that each part is rigidly secured to the other. In particular, the tabs 26 are brazed onto the plate 16; the curled ends of the washer 28 and plate 16 are brazed together; the cylindrical flange 20 of the plate 16 is brazed to the cylindrical flange 42 of the washer 28, and the flange 42 is brazed to the insert 44 at its axially inner end, and at the rounded portion 48.

Thus, the elements of this spool assembly are all held in rigid engagement. The overlapping tab portions of the hub 14 and of the insert 44 particularly aid in resisting endwise thrusts on the head assemblies. The rib portions of the washer also tend to strengthen the head assemblies against axial deflection.

Thus, it will be seen that there is provided in this invention a spool which is simple and rigid in construction, economical to manufacture, and one that will be durable in service.

It will be understood that modifications and variations may be effected without departing from the scope of the novel concept of the present invention.

I claim as my invention:

1. A spool comprising a tubular hub initially provided with axially extending generally rectangular tabs on the ends thereof, a first circular plate at each end of the hub having slots through which said tabs project, a second plate adjacent each of said first plates and having an inturned annular axially extending flange portion, and an insert in said hub concentric therewith having end portions lying inside of said flanges, the projecting ends of said tabs and said insert end portions being bent back against the adjacent plates and secured thereto to prevent outward axial displacement of the plates, each of said second plates having circumferentially spaced recesses including said tabs, the outward wall of

the plate defining said recesses being formed with substantially flat portions which are larger than but of the same general shape as the enclosed tabs, said flat surfaces providing a substantial bearing area for resisting axial loads and coacting with the remaining portions of said second plates to form ribs for stiffening the same.

2. A spool comprising a tubular hub having spaced tabs that initially extend axially, a tubular insert inside said hub and concentric therewith, and a head assembly secured on each end of said hub and on said insert, each head assembly comprising a pair of abutting annular plates, one of said plates having spaced slots through which said tabs project and the other of said plates having an annular axially extending flange receiving said insert, said tabs and the ends of said insert being bent back over said one and said other plates, respectively, to prevent outward axial displacement of said head assemblies, said other plates having a plurality of spaced offset generally rectangular planar portions connected to the remaining portions of the plates by inclined rib members, the offset planar portions being of substantially the same size as the portions of the plates therebetween to divide the plates into inner and outer ribs for reinforcing the head assembly both axially inwardly and axially outwardly to prevent buckling of the same.

GEORGE G. TUCKER, JR.
